UNITED STATES PATENT OFFICE

EDWIN C. WEISGERBER, OF LONG BEACH, CALIFORNIA, ASSIGNOR TO JOHN GRANT,
OF LOS ANGELES, CALIFORNIA

UNDERREAMER

Application filed January 18, 1927. Serial No. 161,758.

This invention relates to a device for operating under the casing of a borehole for a well to enlarge the hole for the reception of the casing and the objects of the invention are to provide a simple and efficient reamer for use particularly in oil wells by which the borehole may be uniformly enlarged and maintained in a straight line, and in which the reaming members may be readily moved to operative and inoperative position, as required. Another object of my invention is to provide a simple reamer by which the reaming or enlargement of a borehole may be accomplished diametrically as well as longitudinally, without interfering with the projected position of the reaming members.

Other objects will appear from the following specification in connection with the accompanying drawings which illustrate a preferred embodiment of the invention and which it will be understood, is exemplary merely of a form in which the invention may be embodied.

In the drawings,

Fig. 1 is an elevation, shown partly in section on line 1—1 of Fig. 5, of a reamer embodying the invention, the cutters being shown in expanded position.

Fig. 1^a is a view similar to Fig. 1, shown partly in section on line 1^a—1^a of Fig. 6, the cutters being in contacted position.

Fig. 2 is a section on line 2—2 Fig. 1.

Fig. 3 is a section on line 3—3 Fig. 1.

Fig. 4 is a plan section on line 4—4 Fig. 1.

Fig. 5 is a plan section on line 5—5 Fig. 1, and

Fig. 6 is a plan section on line 6—6 Fig. 1^a showing the cutters in retracted position.

Referring particularly to the drawing and to the form of embodiment of the present improvement, my invention is shown as comprising a housing 1, reduced at the respective ends to form shoulders 2, and provided with a plurality of equally spaced castellations or extensions 3, for purposes to appear later. Within the housing 1, and arranged for projection and retraction through longitudinal openings 4, by means presently described, is a plurality of cutters or reaming members 6 and 7, which at their respective

ends are provided with ridges 8 and 9, respectively, which co-operate with the inside of said housing to limit the outward projection or movement of said cutters or reaming members 6 and 7, and prevent their disassociation outwardly through the openings 4 and 4' in the housing 1. These cutters or reaming members 6 and 7, as shown in Figs. 4, 5 and 6, are substantially segments and are of widths less than the widths of the openings 2 in the housing 1, in order to permit same to be moved to operative or projected position and to inoperative or retracted position, as will appear later. Each cutter or reaming member 6 and 7, is respectively provided with an arcuate cutting face 6' and 7' of any desirable design which will produce an effective reaming of the borehole, and each cutting face 6' and 7' consists preferably of a multiplicity of acuminate serrations which extend substantially in a horizontal plane, and which are provided intermediate the ends of the segmental cutters 6 and 7. The ends of the segmental cutters 6 and 7 are respectively provided with a plurality of vertical teeth 10 and 11, which function as milling cutters and which, as seen in Fig. 1, are outwardly rounding for the purpose of keeping the cutting faces 6' and 7' out of contact with the wall of the casing 12, during the insertion in and withdrawal of the reamer from the casing, and also to cause the cutters 6 and 7 to be readily moved to retracted position within the housing 1 when, during the withdrawal of the reamer from the reamed borehole, they are brought into contact with the bottom of the casing as will appear later. Each cutter or reaming member 6 and 7, respectively, is provided on each side with arcuate lateral flanges 13 and 14, Figs. 4, 5 and 6, corresponding in outline to and arranged to operate against the inside of the housing 1 to prevent ingress of any of the drilling fluid and of cuttings and other detritus during the operation of the reamer. The inner faces of said segmental cutters 6 and 7 are eccentric to the outer faces 6' and 7', and are provided with a plurality of longitudinal rollers 15 and 16, respectively, which are arranged to be held in place on

such inner faces of the cutters by plates 17 and 18, suitably, but securely fastened in position.

The inner faces of said cutters, that is to say, the roller carrying faces are arranged in contact with the faces of a plurality of cams 19 and 20, mounted, or provided on a stem 21, the rotation in one direction of which operates to move the cutters 6 and 7 outwardly with respect to the housing 1 or to operative position, as shown in Figs. 4 and 5, and the rotation of which cam stem 21 in another direction operates to move the cams 19 and 20 whereby the movement of 10 the cutters 6 and 7 to within the housing 1 may be effected.

Each of the cutters 6 and 7 is formed on one side thereof with a longitudinal extension 6" and 7", respectively which overlap 20 one side of the cams 19 and 20 and which are provided to limit the movement of the cutters 6 and 7, relative to the cams 19 and 20, and prevent wedging of the cutters 6 and 7, between the cams and the housing. The 25 cam stem 21 is arranged to be rigidly connected with the housing 1 and with the drill pipe employed in operating the rotary reamer. For this purpose, the respective ends of the cam stem 21 are squared, as at 30 21', Figs. 2, 3, 4, 5 and 6, and over the squared ends of said stem are fitted collars 22, which are externally threaded, and which are provided with a plurality of equally spaced peripheral recesses 22' for the accommodation 35 of the castellations or extensions 3 formed or provided on the housing 1. By these collars 22, the housing 1 and cam stem 21, are rigidly interlocked, and the connection of the reamer as described with a drill pipe is 40 effected by means of a cap 23, which is internally threaded and is arranged to be screwed onto the collar 22 and onto the externally threaded castellations 3 of the housing 1, whereby the parts so conjoined constitute a complete unit. The cap 23 is provided with the usual threaded extension 23' for connection with a drill pipe, not shown.

A similar cap 24 is provided for threaded 50 engagement with the bottom collar 22, and this cap is provided with an internally threaded socket 24' for a bit or other well drilling apparatus.

The cam stem 21 and also the caps 23 and 55 24 are provided with the usual bore 25 for the drilling fluid used.

In practice, the reamer is inserted through and immediately below the casing 12, the cutters 6 and 7 being retracted during the 60 descent of the reamer through the casing. The reamer being then rotated, the cutting members 6 and 7 are caused to ride over the cams 19 and 20 and to be thrust outwardly beyond the housing 1, as shown in Figs. 1 65 and 5. By this outward projection of the

cutters, the cutting faces thereof are caused to engage the wall of the bore and continuously to ream the borehole during the rotation of the reamer. As the enlargement of the hole proceeds, the cutters 6 and 7, under the resistance offered by the material being cut, continue to move over the faces of the cams 19 and 20 until they reach the limit of their outward thrust or travel, which occurs when the cutters strike the sides of the openings 4 and 4'. 75

When the reaming is completed, the drill stem is operated in a reverse direction, and this operation moves the cams 19 and 20 away from the eccentric faces of the cutters 6 and 7, permitting the latter to assume the contracted positions shown in Figs. 1^a and 6. By operation of the drill pipe, these cutters 6 and 7 may then be caused to ride over the cams in a reverse direction, and thereby to 80 enter the housing 1, so that the cutting faces will not interfere with the withdrawal of the reamer. Should, however, the cutters remain projected, they will be fully retracted or forced inwardly when during the withdrawal of the reamer, the rounding vertical teeth 10 and 11 of the cutters are brought in contact with the end of the casing 12. 85

What I claim, is:

1. An under reamer comprising a housing 95 having longitudinal openings therein, a plurality of reaming members within said housing and normally extending into said openings, said members provided at each end with milling cutters, a stem extending through said housing and provided with means for causing said cutters to move outwardly, means interlocking said housing and stem, and means engaging said interlocking means and formed for connection with a drill pipe. 100

2. An under reamer comprising a housing, having longitudinal openings therein, a plurality of reaming members within said housing and extending into said openings, said members having means for limiting the outward movement thereof and provided at each end with milling cutters, a stem within said housing provided with means for causing the cutting members to move outwardly and permitting same to move inwardly, collars on 110 each end of said stem to interlock said housing and stem, and a cap fitting over one of said collars and having means therein for connection with a drill pipe. 115

3. An under reamer comprising a housing 120 having longitudinal openings therein, a plurality of reaming members within said housing and provided with means for limiting the outward movement of said members, said members having milling cutters at the respective ends thereof, cam means within said housing to cause said members to move outwardly and permit same to move inwardly, and means for interlocking said housing 125 with said cam means. 130

4. An under reamer comprising a housing having longitudinal openings therein, a plurality of reaming members within said housing and arranged for projection through said openings, said members having means 5 for limiting the outward movement thereof, a stem extending through said housing and provided with a plurality of cams for causing said reaming members to move outwardly and permitting same to move inwardly, a 10 collar on each end of said stem for interlocking said housing with said stem, and means engaging one of said collars and formed for connection with a drill pipe. 15
5. An under reamer comprising a housing having longitudinal openings and provided at the ends thereof with spaced extensions, a plurality of reaming members within said housings and operable through said openings, said members having means to limit the 20 outward movement thereof, a stem within said housing provided with means for causing said reaming members to move outwardly and permit same to move inwardly, means 25 for interlocking said stem and housing comprising externally threaded collars fitting over the ends of said stem and formed with recesses for accommodating the extensions of said housing, and means engaging one of said 30 collars and having means for connection with a drill pipe.
6. An under reamer comprising a housing, having longitudinal openings therein, a plurality of reaming cutters within said housing 35 and arranged for projections through said openings, said cutters being less in width than said openings and provided with flanges to prevent the ingress of cuttings and the like into said housing during rotation thereof, cam means within said housing to cause 40 said cutters to be moved outwardly and permit same to move inwardly, collars for conjoining said housing and cam means, and means engaging one of said collars and 45 formed with means for attachment to a drill pipe.
7. In an expansive reamer, an exterior housing with cutter receiving slots, an interior cam member fixed with relation to the 50 housing, said cam member having thereon a radial cam, and a reaming member mounted in the housing slot in contact with the cam and movable in the slot circumferentially about the cam and radially in and out through 55 the slot.
8. In an expansive reamer, a tubular housing having a slotted wall, a reaming member mounted in the wall slot, said reaming member being of such length as to substantially 60 fill the slot in a lengthwise direction and be thereby held against relative lengthwise movement, but being of a circumferential length less than the circumferential length of the slot so as to be allowed relative circumferential movement 65
- within the slot, and a fixed cam member within the housing having a radial cam with which the reaming member contacts and by virtue of which the reaming member is moved outwardly through the housing slot 70 when it moves circumferentially with relation to the cam. 75
9. In an expansive reamer, a tubular housing having a slotted wall, a reaming member mounted in the wall slot, said reaming member being of such length as to substantially fill the slot in a lengthwise direction and be thereby held against relative lengthwise movement, but being of a circumferential length less than the circumferential length of the slot so as to be allowed relative circumferential movement 80
- 85
- 90

In testimony whereof I have set my hand.
EDWIN C. WEISGERBER.
